C. C. HISCOE.

WALL AND CEILING COVERING.

No. 19,601.

Patented Jan. 21, 1890.

UNITED STATES PATENT OFFICE.

CHARLES CONSTANTINE HISCOE, OF NEW YORK, N. Y., ASSIGNOR TO
FREDERICK BECK, OF SAME PLACE.

DESIGN FOR A WALL AND CEILING COVERING.

SPECIFICATION forming part of Design No. 19,601, dated January 21, 1890.

Application filed December 26, 1889. Serial No. 335,037. Term of patent 3½ years.

To all whom it may concern:

Be it known that I, CHARLES CONSTANTINE HISCOE, a citizen of Great Britain, residing at New York, in the county of New York and State of New York, have invented and produced a new and original Design for a Wall and Ceiling Covering, of which the following is a specification, reference being had to the accompanying drawing, forming part thereof.

10 The leading feature of my design consists of an upper border with a molding on each edge, figures 1 and 2, the center being decorated with escaloped shells placed at regular distances, figure 3, the groundwork being a

15 tooled pattern. The center part of the design represents a series of scrolls which interlace and form a continuous pattern. These scrolls have a beaded edge on one side, the other edge being plain, figures 2^A and 3^A. Plain

buttons of different sizes, figures 4 and 5, are placed at intervals, and also beaded rosettes, figure 6. The groundwork consists of wave-like lines, figure 7. A lower border completes this design, having a molding at each edge, figures 8 and 9, and a center filled in with undulating lines, figure 10.

What I claim is—

A design for wall and ceiling covering herein shown and described, consisting of a border in three parts, the upper being escaloped shells, the center dotted scrolls, with plain buttons and beaded rosettes, the lower part being ornamented with undulating lines.

CHARLES CONSTANTINE HISCOE.
